BRUSH ACTUATING MECHANISM FOR
ELECTRIC MOTORSVincent J. Winkel, Wausau, Wis., assignor of
one-half to Fred M. Winkel, Brooklyn, N. Y.

Application April 4, 1933, Serial No. 664,304

11 Claims. (Cl. 172—279)

This invention relates to improvements in brush actuating mechanisms for electric motors, and more particularly to brush mechanisms of repulsion-induction motors, in which at least one pair of short circuited brushes is employed in starting the motor, which brushes are lifted away from the commutator after the motor has reached a predetermined speed.

One object of my invention is to provide a brush mechanism which is actuated by electromagnetic influence to bring the brushes into contact with the commutator.

Another object is to provide a mechanism which is simple, inexpensive to manufacture, efficient and noiseless in operation.

Another object is to provide certain improvements in the form, construction and arrangement of the several parts whereby the above named and other objects may effectively be attained.

A practical embodiment of my invention is represented in the accompanying drawings, in which

Fig. 1 represents a detail vertical section of so much of a repulsion-induction motor as will sufficiently illustrate the application of my improved brush actuating mechanism thereto with the brushes in their operative position;

Fig. 2 represents a detail plan view of the parts shown in Fig. 1;

Fig. 3 represents a vertical section taken in the plane of the line III—III of Fig. 1, looking in the direction of the arrows;

Fig. 4 represents a similar view with the parts in another position;

Fig. 5 represents a detail top plan of one of the brushes and the holder;

Fig. 6 represents a diagrammatic view of the electrical connection between the commutator bars and the magnetic coils;

Fig. 7 represents a detail vertical section similar to Fig. 3 and illustrating a modified form of electromagnet, and

Fig. 8 represents a diagrammatic view of the electrical connection between the commutator bars and the magnetic coils.

In the form shown in Figs. 1 to 6 inclusive, the shaft of the motor is denoted by 1, the rotor by 2, the bars forming the commutator by 3 and the stator by 4. In the drawings only two brushes 5 are shown in coaction with the bars of the commutator in the usual manner, although any suitable number may be employed. Each brush 5 is slidably mounted in a tubular holder 6 formed in a support 7 fixed to extend laterally from a ring 8 carried by the frame 9 of the motor.

The brush 5 is mounted in position to be moved in its holder 6 into contact with the commutator by means of a flat coil spring 10, one end of which is fixed to a pin 11 secured to the ring 8, while the free end engages the brush and moves therewith in a cut-away portion 12 of the holder 6. A curved armature 13 is pivoted at 14 on the outer end of the support 7 and is provided with a finger 15 arranged in position to extend into a recess 16 formed in the holder 6, the wall 17 of which recess 16 limits the downward movement of the finger 15. The upward movement of the finger 15 brings it into contact with an offset portion 18 of the brush 5 which projects into the recess 16 and lifts the brush away from the commutator. A spiral spring 19 interposed between the finger 15 and a lug 20 on the support 7 serves to normally hold the armature and finger in their upward position and the brush away from the commutator. The downward movement of the armature 13 and finger 15 is accomplished by means of an electromagnet composed, in the present instance, of two concentric coils of wire 21, 22 wound in annular recesses 23, 24 respectively, formed in a steel core 25. The coils 21, 22 are connected to the bars 3 of the commutator by leads which have their ends permanently fastened to the bars in any well known or approved manner. The core 25 is mounted to rotate with the shaft 1 and insulated therefrom by an insulating sleeve 26.

To obtain a maximum magnetic attraction from the electromagnet, the coils 21, 22 are connected to the bars of the commutator 90 electrical degrees apart, as shown diagrammatically in Fig. 6, which arrangement provides a two-phase effect. When electrical energy is applied to the stator 4, a current is induced in the rotor which, in turn, sets up a magnetic influence in the coils 21, 22 and core 25. This secondary current from the rotor to the coils and core creates a magnetic attraction sufficient to move the armature 13 toward the coils and core against the tension of the spring 19 and causes the finger 15 to move away from the offset portion 18 of the brush 5 to the wall 17 of the recess 16, while the spring 10 exerts its pressure on the brush to force it onto the commutator bars.

The pivotal mounting of the curved armature 13 on the support 7 and the position of the finger, when resting on the wall of the recess 16, serve to space the armature a slight distance from the periphery of the core, thereby forming a small gap between the armature and core and thus preventing noisy contact of the parts. As the rotor nears a predetermined speed, a suitable device 27, pref-

erably a speed responsive device, of any well known or approved type, is arranged to be brought into contact with the ends of the commutator bars 3 to short circuit the commutator and thereby 5 de-energize the coils 21, 22 and core 25 thus permitting the motor to run as an induction motor.

When the magnetic influence of the coils 21, 22 and core 25 is broken, the spring 19 is free to pull the armature away from the coils and core, 10 while the finger 15 in moving with the armature lifts the brush 5 against the tension of its spring 10 away from the commutator bars 3, thereby eliminating all wear on the brush and commutator after the motor has attained its full speed.

15 In order to minimize eddy currents in the body of the core 25, a series of radially arranged slots 28 are disposed in the core, which slots extend from the periphery of the core to a point inwardly of the bottom of the annular recesses 23, 24. 20 One radially disposed slot 29 is extended from the periphery of the core to the insulating sleeve 26 to avoid a closed secondary circuit for the coils 21, 22.

The brushes 5 are connected by leads 30 25 screwed to the ring 8 at 31.

While I have shown in Figs. 1 to 6 inclusive and have described a core having two annular grooves provided with coils of wire therein, which coils are connected to the bars of the commutator at 30 90 electrical degrees apart to form a two-phase electromagnet, I wish it understood that three annular grooves 32, 33, 34 and coils 35, 36, 37 may be disposed on the core 38, as shown in Fig. 7 and diagrammatically in Fig. 8, in which form the 35 leads of the coils are connected to the bars of the commutator at 120 electrical degrees apart, thereby forming a three-phase electromagnet. By this last named arrangement of the coils and their connections with the bars of the commutator, I 40 find that a more uniform influence or pull is exerted throughout the full revolution of the rotor.

It will be understood that various changes may be resorted to in the form, construction and arrangement of the several parts without departing from the spirit and scope of my invention, and hence, I do not intend to be limited to the details herein shown and described except as they 45 may be included in the claims.

What I claim is:

50 1. In combination with the rotor and commutator of a repulsion-induction motor, of a stationary holder, a spring pressed brush slidable therein, an oscillating armature for controlling the movement of the brush, means normally holding the brush out of contact with the commutator, and electromagnetic means coacting with the armature for actuating the holding means to allow the brush to move into contact with the commutator, said electromagnetic means comprising a core mounted to rotate with the rotor and provided with a plurality of annular recesses, a concentrically wound coil in each of said recesses, said coils being connected to the commutator and energized by current induced in the 55 rotor.

60 2. In combination with the rotor and commutator of a repulsion-induction motor, of a stationary holder, a spring pressed brush slidable therein, an oscillating armature mounted on said holder for controlling the movement of the brush, means normally holding the brush out of contact with the commutator, and electromagnetic means coacting with the armature for actuating the holding means to allow the brush to move into contact with the commutator, said electromagnetic means

comprising a core mounted to rotate with the rotor and provided with a plurality of annular recesses, a concentrically wound coil in each of said recesses, said coils being connected to the commutator and energized by current induced in the 80 rotor.

3. In combination with the rotor and commutator of a repulsion-induction motor, of a stationary holder, a spring pressed brush slidable therein, an oscillating armature mounted on said holder, means on the armature for controlling the movement of the brush and normally holding the brush out of contact with the commutator, and electromagnetic means coacting with the armature for actuating the means on the armature to allow the brush to move into contact with the commutator, said electromagnetic means comprising a core mounted to rotate with the rotor and provided with a plurality of annular recesses, a concentrically wound coil in each of said recesses, said coils being connected to the commutator and energized by current induced in the 85 rotor.

4. In combination with the rotor and commutator of a repulsion-induction motor, of a stationary holder, a spring pressed brush slidable therein, an oscillating armature for controlling the position of the brush with respect to the commutator, electromagnetic means coacting with the armature to permit the brush to move 100 into contact with the commutator, said electromagnetic means comprising a core mounted to rotate with the rotor and provided with a plurality of annular recesses, a concentrically wound coil in each of said recesses, said coils being connected to the commutator and energized by current induced in the rotor, and automatic means for short circuiting the coils to release the armature and move the brush out of contact with the commutator when the rotor reaches a predetermined speed.

5. In combination with the rotor and commutator of a repulsion-induction motor, of a stationary holder, a spring pressed brush slidable therein, an oscillating armature, means thereon 105 for controlling the position of the brush with respect to the commutator, electromagnetic means coacting with the armature to permit the brush to move into contact with the commutator, said electromagnetic means comprising a core mounted to rotate with the rotor and provided with a plurality of annular recesses, a concentrically wound coil in each of said recesses, said coils being connected to the commutator and energized by current induced in the rotor, and 110 automatic means for short circuiting the coils to release the armature and move the brush out of contact with the commutator when the rotor reaches a predetermined speed.

6. In combination with the rotor and commutator of a repulsion-induction motor, of a stationary holder, a spring pressed brush slidable therein, an oscillating armature mounted on said holder for controlling the position of the brush with respect to the commutator, electromagnetic 115 means coacting with the armature to permit the brush to move into contact with the commutator, said electromagnetic means comprising a core mounted to rotate with the rotor and provided with a plurality of annular recesses, a concentrically wound coil in each of said recesses, said coils being connected to the commutator and energized by current induced in the rotor, and 120 automatic means for short circuiting the coils to release the armature and move the brush out of contact with the commutator when the rotor reaches a predetermined speed.

7. In combination with the rotor and commutator of a repulsion-induction motor, of a stationary holder, a spring pressed brush slidable therein, an oscillating armature mounted on said holder for controlling the movement of the brush, electromagnetic means coacting with the armature to permit the brush to move into contact with the commutator, said electromagnetic means comprising a core mounted to rotate with the rotor and provided with a plurality of annular recesses, a concentrically wound coil in each of said recesses, said coils being connected to the commutator and energized by current induced in the rotor, and 130 automatic means for short circuiting the coils to release the armature and move the brush out of contact with the commutator when the rotor reaches a predetermined speed.

8. In combination with the rotor and commutator of a repulsion-induction motor, of a stationary holder, a spring pressed brush slidable therein, an oscillating armature mounted on said holder for controlling the position of the brush with respect to the commutator, electromagnetic 135 means coacting with the armature to permit the brush to move into contact with the commutator, said electromagnetic means comprising a core mounted to rotate with the rotor and provided with a plurality of annular recesses, a concentrically wound coil in each of said recesses, said coils being connected to the commutator and energized by current induced in the rotor, and 140 automatic means for short circuiting the coils to release the armature and move the brush out of contact with the commutator when the rotor reaches a predetermined speed.

9. In combination with the rotor and commutator of a repulsion-induction motor, of a stationary holder, a spring pressed brush slidable therein, an oscillating armature mounted on said holder for controlling the movement of the brush, electromagnetic means coacting with the armature to permit the brush to move into contact with the commutator, said electromagnetic means comprising a core mounted to rotate with the rotor and provided with a plurality of annular recesses, a concentrically wound coil in each of said recesses, said coils being connected to the commutator and energized by current induced in the rotor, and 145 automatic means for short circuiting the coils to release the armature and move the brush out of contact with the commutator when the rotor reaches a predetermined speed.

of contact with the commutator when the rotor reaches a predetermined speed.

7. In combination with the rotor and commutator of a repulsion-induction motor, of a stationary holder, a spring pressed brush slidable therein, an oscillating armature mounted on said holder, means on the armature for controlling the position of the brush with respect to the commutator, electromagnetic means coacting with the armature to permit the brush to move into contact with the commutator, said electromagnetic means comprising a core mounted to rotate with the rotor and provided with a plurality of annular recesses, a concentrically wound coil in each of said recesses, said coils being connected to the commutator and energized by current induced in the rotor, and automatic means for short circuiting the coils to release the armature and move the brush out of contact with the commutator when the rotor reaches a predetermined speed.

8. In combination with the rotor and commutator of a repulsion-induction motor, of a stationary holder, a spring pressed brush slidable therein, an oscillating armature mounted on said holder and arranged to engage the brush to hold it out of contact with the commutator, and electromagnetic means energized by current induced in the rotor and arranged to coact with the armature to permit the brush to move into contact with the commutator, said electromagnetic means comprising a core and a plurality of coils wound thereon, said coils being connected to the commutator.

35 9. In combination with the rotor and commutator of a repulsion-induction motor, of a stationary holder, a spring pressed brush slidable therein, an oscillating armature mounted on said holder and arranged to engage the brush to hold it out of contact with the commutator, and electromagnetic means energized by current induced in the rotor and arranged to coact with the ar-

mature to permit the brush to move into contact with the commutator, said electromagnetic means comprising a core mounted to rotate with the rotor and a plurality of coils concentrically wound thereon, said coils being connected to the commutator.

10. In combination with the rotor and commutator of a repulsion-induction motor, of a stationary holder, a spring pressed brush slidable therein, an oscillating armature mounted on said holder and arranged to engage the brush to hold it out of contact with the commutator, electromagnetic means energized by current induced in the rotor and arranged to coact with the armature to permit the brush to move into contact with the commutator, said electromagnetic means comprising a core and a plurality of coils wound thereon, said coils being connected to the commutator, and automatic means for short circuiting the coils to release the armature and move the brush out of contact with the commutator when the rotor reaches a predetermined speed.

11. In combination with the rotor and commutator of a repulsion-induction motor, of a stationary holder, a spring pressed brush slidable therein, an oscillating armature mounted on said holder and arranged to engage the brush to hold it out of contact with the commutator, electromagnetic means energized by current induced in the rotor and arranged to coact with the armature to permit the brush to move into contact with the commutator, said electromagnetic means comprising a core mounted to rotate with the rotor and a plurality of coils concentrically wound thereon, said coils being connected to the commutator, and automatic means for short circuiting the coils to release the armature and move the brush out of contact with the commutator when the rotor reaches a predetermined speed.
